UNITED STATES PATENT OFFICE.

RICHARD F. BURFEIND, OF PHILADELPHIA, PENNSYLVANIA, ASSIGNOR TO KEYSTONE TYPE FOUNDRY, OF PHILADELPHIA, PENNSYLVANIA, A CORPORATION OF PENNSYLVANIA.

DESIGN FOR A FONT OF TYPE.

51,254.

Specification for Design.

Patented Sept. 11, 1917.

Application filed June 20, 1914. Serial No. 846,390. Term of patent 14 years.

To all whom it may concern:

Be it known that I, RICHARD F. BURFEIND, a citizen of the United States, residing at Philadelphia, Philadelphia county, and State of Pennsylvania, have invented a certain new, original, and ornamental Design for a Font of Type, of which the following is a specification.

The accompanying drawing which is made a part hereof and to which reference is made, shows the face and form of each letter and character composing said font of type, as well as the ornamental character of the font as a whole.

Copies of this patent may be obtained for five cents each, by addressing the "Commissioner of Patents, Washington, D. C."

What I claim is:

The ornamental design for a font of type shown in the accompanying drawing.

In witness whereof, I have hereunto set my hand and seal at Philadelphia, Pennsylvania this 16th day of May, A. D. nineteen hundred and fourteen.

RICHARD F. BURFEIND. [L. S.]
